FIG. 3

INVENTOR
LOUIS W. REINHARDT
BY *Ansprey*
ATTY.

UNITED STATES PATENT OFFICE.

LOUIS W. REINHARDT, OF BROCKTON, MASSACHUSETTS, ASSIGNOR TO GEORGE E. BELCHER, OF STOUGHTON, MASSACHUSETTS.

SHOE-FORM.

1,118,582.

Specification of Letters Patent. Patented Nov. 24, 1914.

Application filed April 11, 1914. Serial No. 831,316.

To all whom it may concern:

Be it known that I, LOUIS W. REINHARDT, a citizen of the United States, residing at Brockton, county of Plymouth, Commonwealth of Massachusetts, have invented certain new and useful Improvements in Shoe-Forms, of which the following is a specification.

This invention relates to shoe forms and particularly to an automatically adjustable shoe form.

Shoe forms as at present constructed are either mechanically adjusted by the operator or have an automatic adjustment. Where the form was mechanically adjustable it was open to several objections. The construction was not only expensive and usually complicated but in use it was possible to injure the shoe by applying too great a pressure to the interior thereof in effecting the adjustment. Those forms which have been automatically adjustable have so far as is known to me been of the type wherein the adjustment was effected by a longitudinal sliding movement of the heel part of the form relative to the toe part. Such forms have usually consisted of either a shell or a solid toe part, and a skeleton heel part usually in the form of a yoke shaped piece of metal adapted when the form was inserted into a shoe to be forced against the counter of the shoe under the action of a pair of coil springs. The shortening of the form to admit of its being inserted into the shoe and the form subsequently expanded has been usually effected by slotting both arms of the yoke near their free ends to receive studs on the toe part of the form. This permitted the yoke to be moved up toward the toe part by a relative sliding movement against the resistance of the two interposed coil springs, thereby shortening the form to admit of its insertion into the shoe. When the form was positioned within the shoe, the pressure on the yoke was removed to permit it to spring back against the counter of the shoe under the action of the released coil springs. This type of shoe form has found favor in the trade because of its simplicity and convenience of operation, and it is to this general class that my present invention is appropriated.

It is the object of my present invention to improve and perfect the automatically adjustable shoe forms as now constructed. In my invention, the adjustment of the shoe

form is effected by moving the heel part of the form up toward the toe part, thereby shortening the form so that it may be readily inserted within a shoe, and automatically lengthened to fill the shoe and maintain it in its proper shape. The mechanism for effecting this adjustment is materially different both in principle and construction from the pin and slot constructions of the forms now in use. Briefly, such construction comprises a pair of levers pivoted to the toe part of the form and flexibly connected with the heel part so as to permit the heel part to move up toward the toe part when the levers are rocked on their pivots.

The construction and operation of my invention will be more fully disclosed in the specification which follows. In the drawings forming a part of that specification, I have shown as an illustrative embodiment a construction of shoe form which has been found efficient and satisfactory in use and well adapted to the requirements of manufacture.

Throughout specification and drawings like reference numerals are correspondingly applied and in these drawings: Figure 1 is a longitudinal section through a shoe form in accordance with my invention, the form being shown in normal lengthened position. Fig. 2 is a similar view showing the form in shortened position. Fig. 3 is a vertical section on the line 3-3 of Fig. 2, and Fig. 4 is a detail of one of the levers hereinafter referred to.

The shoe form of my present invention consists of a heel part 1 and a toe part 2, pivotally connected with each other by a pair of pivoted levers 7, so as to be capable of shortening to admit of the form being inserted in a shoe to automatically lengthen and fill the shoe and maintain it in proper shape. The heel and toe parts are preferably in the form of shells or skeletons, made of some material which may be molded to shape and which after being molded to shape will set and harden so as to present sufficient rigidity to firmly hold the shoe in shape when inserted therein. I have found leatherboard or like material particularly well suited for this purpose and in the embodiment selected have shown the shoe form as made of this material. Obviously however I do not limit myself to this or any other material. In fact, the parts of the form could be solid if desired. The

edges of the sole portion of the fore part are connected up at the points indicated by the numerals 3 and 4 respectively, Fig. 1, in any well known manner. The rear ends 5 of the toe part shell and the front ends of the heel part shell overlap each other. For convenience of reference the pair of extensions or tongues of the heel part will be designated by the numeral 1¹ and those of the toe part by the numeral 2¹. Near the rear ends of the extensions 2¹ and on each side thereof I secure, preferably by riveting, a stud 5 having its outer end clenched in the material of the extension and having at its inner end a relatively large head 6. The studs 5 project inwardly a sufficient distance to accommodate the forwardly extending tongues 1¹ of the heel part between their heads 6 and thelapping rearwardly extending tongues 2¹ of the toe part. The tongues 1¹ normally rest and find bearing on the studs and turn on the studs in the adjusting movements of the heel part.

The numeral 7 indicates a pair of levers having holes near their lower ends to fit the pivot studs. The lower ends of the levers 7 lie between the heads 6 of the pivots 5 and the tongues 1¹. The levers pivotally connect the parts of the form and turn on the studs 5 in the shortening and lengthening movements of the heel part. At their upper ends they are fastened to the tongues 1¹ in any suitable manner as by the rivets 8. The levers are preferably so disposed relative to the tongues 1¹ as to normally lie diagonally thereof. This positions their link portions 9 directly in the line of application of the shortening pressure, (see Fig. 1.) When the form is shortened the levers 40 swing forwardly on their pivots 5 and assume a vertical position substantially at right angles to the plane of movement of the heel part. (See Fig. 2).

The link portion 9 of each lever extends 45 downwardly and rearwardly from the lever between its ends. Each link 9 has a tongue 10 struck out from its lower end so as to lie on the inner side of the link. The tongues 10 serve to fasten the front ends of a pair 50 of springs 11 to the links and are so disposed as to receive the shortening pressure imparted to the springs direct and transmit it to the levers to rock the same. The springs 11 may be spiral springs if desired and may have 55 any desired number of convolutions. They are fastened at their rear ends to the heel part above the line of the pivot studs 5 in any desired manner as by brads 12 driven through the sides of the heel part and clenched over the rear ends of the springs. The springs 11 are compressed when the 60 form is shortened and when the pressure is removed serve to force the heel part back against the counter of the shoe.

65 In use, the form is shortened by forcing

the heel part up toward the toe part. The shortening pressure is received by the springs 11 and transmitted to the tongues 10 of the links. The links being directly in the line of application of the pressure receive 70 and transmit the pressure directly to the levers with practically no lost motion. This rocks the levers forwardly on their pivots 5, allowing the heel part to ride up toward the toe part. The forward motion of the 75 heel part is limited and stopped by the shoulders 13 of the tongues 1¹ moving up against the studs 5. The form is now shortened and may be readily inserted within the shoe by swinging the heel part upwardly on its pivots to facilitate entrance of the form into the shoe. The form is then inserted into the shoe and lengthened to original position therein by releasing the heel part which will be forced back against the counter of the 80 shoe by the action of the springs 11. This lengthening of the form serves to expand the shoe and maintain it in proper position. To remove the form it is only necessary to force the heel part forward toward the toe part, 90 swing the heel upwardly and pull the toe part out of the shoe.

Obviously the range of expansion of the form may be increased or diminished by increasing or diminishing the length of the 95 levers 7 and providing springs of corresponding size and power.

Various other modifications in the form and construction of my device may obviously be resorted to without departing from 100 the spirit of my invention if within the limits of the appended claims.

What I therefore claim and desire to secure by Letters Patent is:—

1. A shoe form comprising a pair of relatively movable shell-like form parts, a pair of oppositely disposed devices mounted for oscillation through arcs longitudinally of the form by a relative movement of the form parts and each having its opposite ends pivotally connected each with a form part, and means resiliently connecting said devices to one of said form parts and normally tending to hold the form in one of its two effective 105 positions. 110

2. A shoe form comprising a pair of relatively movable shell-like form parts, a pair of oppositely disposed levers mounted for oscillation through arcs longitudinally of the form by a relative movement of the form parts and each having its opposite ends pivotally connected each with a form part and springs connecting said levers to one of said form parts and normally tending to hold the form in one of its two effective 115 positions. 120

3. A shoe form comprising a fixed and a movable part, oscillatory devices pivotally connected near their ends with said parts whereby the form may be shortened and lengthened and springs connecting said de- 130

vices to said movable part at a point above one set of pivots for said devices and normally tending to hold the form in lengthened position.

5. A shoe form comprising a fixed and a movable part, having lapping extensions, oscillatory members pivotally connecting said extensions whereby the form may be shortened and lengthened by a relative 10 movement of the form parts to oscillate said members on their pivots, and means normally tending to hold the form in one of its two effective positions.

5. A shoe form comprising a fore part and 15 a heel part, rocking members pivotally connecting said form parts and rocked on their pivots by a relative movement of the parts whereby the form may be shortened and lengthened, extensions on said rocking members, engaging devices on said extensions, and flexible connections engaged at one end with said devices and at their other ends with one of said form parts and normally tending to hold the form parts in lengthened position.

6. A shoe form comprising a fore part and a heel part, studs set up in said fore part, levers pivotally mounted on said studs and normally disposed in angular relation to 30 said form parts and fixedly connected with one of said form parts whereby the form may be shortened and lengthened, extensions on said levers between the ends of the levers, tongues on said extensions effectiely disposed to receive the shortening pressure, and flexible connections engaged at one end with 35 said tongues and at their other ends with one of said form parts and normally tending to hold the form parts in lengthened position.

7. A shoe form comprising a fore part and a heel part, having lapping extensions, studs set up in the lapping extensions of the fore part, levers pivotally mounted on said studs and fixedly connected with the lapping extensions of the heel part, whereby the form may be shortened and lengthened, extensions on said levers, tongues on said extensions, and springs engaged at one end with said

tongues and at their heads with one of 50 said form parts above the line of the studs and normally tending to hold the form parts in lengthened position.

8. A shoe form comprising a fixed and a movable part, means pivotally connecting 55 said parts whereby the form may be shortened and lengthened, and pivots for said connecting means and constituting stops against which said movable part contacts to limit the movement of said movable part in 60 one direction.

9. A shoe form comprising a fixed and a movable part having each lapping extensions, and the extensions of said movable part being shouldered, means pivotally connecting said form parts, whereby the form may be shortened and lengthened and pivots for said connecting means and constituting 65 stops against which the shoulders of the extensions of said movable part contact to 70 limit the movement of said form part in one direction.

10. A shoe form comprising a pair of relatively movable shell-like parts, a link connected to each of said parts, for pivotal 75 movement only and disposed substantially vertically of the form permitting said parts movement in arcs longitudinally of said form in the relative movement of the parts, and resilient means for holding the parts 80 yieldingly expanded.

11. A shoe form comprising a pair of relatively movable parts, a link connected to each of said parts for pivotal movement only and disposed substantially vertically of the 85 form permitting said parts movement in arcs longitudinally of said form in the relative movement of the parts, and a spring member effective between said parts to hold said link with its pivots at opposite ends of said 90 arcs.

In testimony whereof I affix my signature in presence of two witnesses.

LOUIS W. REINHARDT.
